Attorney

UNITED STATES PATENT OFFICE.

ALFRED C. BARROW, OF LYNCHBURG, VIRGINIA, ASSIGNOR TO A. C. BARROW & COMPANY, OF LYNCHBURG, VIRGINIA, A CORPORATION OF VIRGINIA.

PATCH POCKET.

Application filed May 5, 1922. Serial No. 558,669.

To all whom it may concern:

Be it known that I, ALFRED C. BARROW, a citizen of the United States, residing at Lynchburg, in the county of Campbell and State of Virginia, have invented certain new and useful Improvements in Patch Pockets; and I do hereby declare the following to be a full, clear, and exact description of the invention, such as will enable others skilled in the art to which it appertains to make and use the same.

This invention relates to improvements in overalls or work garments, and more particularly to an improved patch pocket therefor.

It is well known that the bottom of the pockets of work garments wear out very quickly due to the miscellaneous objects carried in the pockets and it is, therefore, an object of invention to overcome this weakness by providing a reinforced pocket which can be cheaply manufactured and which shall be highly efficient in use.

The various features of novelty of the invention will appear from the detailed description thereof taken in connection with the accompanying drawing forming part of the specification.

In the drawings,

Figure 1 is a view of the piece from which the improved patch pocket is made;

Fig. 2 is a view showing the lower part of the piece doubled and stitched to the main body portion of the piece and incidentally the upper edge hemmed;

Fig. 3 shows the side edges hemmed;

Fig. 4 shows the bottom corners turned over preparatory to attaching the piece to the body of the garment, and

Fig. 5 shows the piece attached to the body of the garment.

In the drawings, 10 indicates the piece of fabric or facing from which the improved pocket is made, 10' indicating a flap or extension of the same. This flap is preferably of less width than the main body of the piece and is turned and stitched along its transverse edge to the body of the piece or fabric 10 as shown at 11. The top of the piece is hemmed as shown at 12 and the piece is then ready for attachment to

the body 13 of the garment. In attaching the piece to the body 13 of the garment, the side edges are first turned as at 14 and the bottom corners also turned as at 15 and the side edges and bottom thereof then stitched to the body as clearly shown in Fig. 5, numeral 16 indicating such stitching.

The above described construction provides a reinforced pocket which can be cheaply manufactured and which is efficient in use. By providing a flap 10' at the bottom of the main piece 10 and doubling said flap and stitching it to the main body portion of said piece not only is the manufacturing operations reduced to the simplest possible state, but a superior reinforced pocket is obtained than is the case where the flap 10' is a detached member which is sewed on to the outside of the pocket as is customary. It is to be noted that the flap 10' is turned to lie inside the pocket rather than outside, a feature which makes it unnecessary to hem the edge 10^a of the flap. The flap is preferably of less width than the main body of the piece 10 so as to avoid unnecessary thickness of material when the side edges of the piece 10 are turned. By turning the corners 15 as shown, a neater appearing pocket is provided but such turning is optional as regards the main feature of the invention, which is the doubling of the lower end of the piece 10 and stitching the transverse edge of said flap to the main body portion of said piece. The flap extends upwardly a sufficient distance to take the wear which ordinarily comes at the bottom of the pocket.

The above described invention is extremely simple but marks a decided improvement in the art inasmuch as the reinforcement is obtained by turning under the portion of the piece which comprises the main body portion of the pocket.

What I claim is:

1. The combination with a garment body, of a facing for forming a pocket therewith, stitching securing the sides and lower end of the facing to the said body, the lower end of the facing being doubled over to form a reinforce for the bottom of the pocket, said doubled over portion extending

upwardly and stitched at its upper edge to the facing above the stitching at the bottom of the pocket.

2. The combination as in claim 1, characterized by the said doubled over portion being disposed between the facing and the garment body.

3. The combination as in claim 1, characterized by this that the width of the doubled over portion is less than the width of the facing proper when laid out flat. ¹⁰

In testimony whereof I affix my signature.

ALFRED C. BARROW.
